COLLAPSIBLE INSULATING CASING

Philip Zalkind, New York, N. Y.

Original application April 20, 1936, Serial No. 75,315. Divided and this application August 17, 1939, Serial No. 290,582

1 Claim. (Cl. 229—14)

My invention is a division of my application Serial No. 75,315, filed April 20, 1936, now matured into Patent No. 2,173,871 and relates to novel heat insulated containers, and more particularly relates to folding or collapsible containers.

My invention comprises a container formed from blanks of sheet material, such as corrugated board, box board and the like, cut, scored and folded in a manner to provide a casing having hollow walls. These hollow walls provide dead air spaces which effectively insulate the container against the passage of heat. Thus, with my construction a container is provided which may be folded or collapsed, and at the same time is an efficient heat insulator. Such a container may be used for the storage of either hot or cold materials, which are to be maintained either hot or cold as the case may be. Thus my container is particularly adapted to the shipment of ice-cream and the like, but I do not limit its use to this particular purpose. My container is inexpensive to construct. It may be stored in knock down condition and may be so delivered to the user. It therefore requires comparatively little space for storing, and cost of delivery will be relatively low. Moreover, where additional heat insulation is required, my container is adapted to receive filler members which provide such additional heat insulation. These members may be of any well known type, but where such additional insulation is necessary, I prefer to use one of the types of insulating filler disclosed in my copending applications Serial Nos. 75,314, now matured into Patent No. 2,231,982, and 75,316.

The objects of my invention are thus to provide a container that may be collapsed or folded, that provides insulation against the passage of heat, that is inexpensive to construct, and that is adapted to receive an insulating filler. There are other objects of my invention which will be apparent from the following detailed description in connection with the drawing, in which:

Figure 1 is a perspective view, partly cut away, showing a modified form of my novel container.

Figure 2 is a developed view of a blank for forming the inner shell shown in Figure 1.

Figure 3 is a perspective view showing the shell of Figure 2 in a collapsed condition.

Figure 4 is a perspective view showing the inner shell of Figures 2 and 3 assembled for insertion into the outer shell as shown in Figure 1.

Figure 5 is a developed view of a blank for forming the cover shown in Figure 1.

Referring now to Figures 1 to 5, I have shown a preferred embodiment of my invention. In this

modification the outer casing comprises a plain rectangular tube which may be made from an integral rectangular blank of sheet material having parallel score lines which divide the blank into the four side wall members of the tube, such as members 80, 81, 82 and 83 of Figure 1. The tube is preferably formed by uniting the outside edges of the blank by means of tape provided with an adhesive coating which overlaps both of the 10 end panels of the blank. However, an additional flap may be provided for making a lap joint; or the tube may be joined on the face of a side member rather than at a corner of the tube.

A suitable blank for the inner shell is shown 15 in Figure 9. The blank shown in this figure comprises four side walls 91 to 94, each separated by a series of parallel score lines, as, for example, 95, 96 and 97, thus providing two narrow panels, as, for instance, 99 and 100 extending between 20 each two main panels. When the blank is assembled the two narrow panels of each pair lie in face to face relationship with each other and may be united with each other in a suitable manner, as, for instance, by the use of an adhesive 25 substance. Each pair of narrow panels so united forms a spacing member 98, which is clearly shown in Figures 1, 3 and 4.

Protruding from each of the side wall sections 30 at the top and bottom thereof are end wall closure sections 101 and 102 separated from their individual side wall sections by the score lines 103 and 104, and 107 and 108. Extending from the end wall sections 91 and 94 are the tabs 105 and 106. These tabs are used in forming the 35 blank into a tube, the tabs 105 and 106 being placed in face to face relationship with each other, and joined to each other in any suitable manner, as, for instance, by gluing. In this manner an additional spacer member 99 is formed 40 in addition to those formed by the pairs of narrow panels between the main panels, as I have previously described. A collapsed tube thus formed is shown in Figure 3.

To assemble the shell from the collapsed tube, the side walls 91 and 94 are turned on their score lines until the side walls are in proper angular relationship to each other. For a rectangular casing, of course, each wall should be at a right angle to its adjoining wall. When the tube has 45 been expanded into proper position, as described above, the end sections 101 are turned about their score lines 103 and 104 until the narrow sections 109 between the score lines 103 and 104 are in face to face relationship with their corresponding side wall sections 91—94. The sec-

tions 101 are then further turned about their score lines 104 until they are at right angles to the side wall sections to form the top end closure for the inner shell. The bottom sections 102 may then be folded on score lines 107 and 108 in a similar manner to that described above for the top end. That is, the bottom end flaps are folded until the narrow panels 110 between the score lines 107 and 108 are in face to face relationship to their respective side walls 91 to 94, and the end sections 102 are then folded to be perpendicular to the side walls. The narrow panels 109, in conjunction with the top edge of their respective side walls, form a peripheral outstanding flange at the top edge of the shell, as is clearly shown in Figure 4, which shows an expanded and assembled inner shell as viewed from the top. A similar peripheral flange is formed by the panels 110 at the bottom of the shell.

To complete the insulated casing the inner shell is placed within the outer shell, as is shown in Figure 1, the space flanges 98 at the corners of the inner shell fitting snugly within inner corners of the outer shell. Pan shaped closures 111 are then applied to the upper and lower end of the outer casing.

A blank for such a suitable end closure is shown in Figure 5. It comprises merely a main section 112 with four side flaps as at 113 and separated from the main section by the score lines 90. The member 111 formed by bending the flaps 113 on the score lines 90 is proportioned to fit snugly within the outer shell of the casing. It can be seen that this casing may be easily assembled and may be easily recollapsed for shipment after use.

When the shell is assembled as described above, six separated "dead" air spaces are provided for insulating the container. Thus, a single side wall panel of the inner shell, the two spacing members 98 at each side of the panel, the corresponding side wall of the outer shell, and a section of each of the pan-shaped closure member form a "dead" air space isolated from the other spaces between the two shells; and each of the four walls is thus provided with its isolated air space. At each end of the container an isolated "dead" air space is provided by the pan-shaped member abutting the outstanding peripheral flange formed on the closure of the inner shell. It will be, of course, understood that, by properly proportioning the various flanges and panels, the thickness of the "dead" air space may be adjusted to any desired value depending upon the particular application.

It will be noted that the inner casing just described may be used with the outer casing shown in my Patent 2,173,871. In this event, the top ends of the flanges 98 may be removed, as shown in Figure 4 at 89, so as to match the hollow reinforcement around the top edge of the outer shell of Figures 1, 2 and 4 of Patent 2,173,871. Where this outer shell is used with the inner shell shown in Figure 4, the bottom end closure on the outer shell may be provided in the outer shell blank, and the top end closure may be a hollow plug member, and designed to fit within the outstanding flange provided by the top closure of the shell of Figure 4. It will be further understood that various other combinations may be used, as, for instance, the inner shell shown in Figure 4 may be used with an outer shell having a bottom end closure, as shown in Figure 1 and a top end closure, as shown in Figure 1.

While I have shown my casing to be rectangular in cross-section, it may be hexagonal or octagonal just as readily, by providing the proper number of sidewall panels, and the tube so formed may be collapsed in the same manner, as is shown in Figure 3 for the rectangular tube. Thus, for a hexagonal casing of the blank of Figure 2 will have six main panels, such as panels 91, and the closure panels 101 and 102 will be hexagonal. It is not necessary to provide a closure panel, such as panel 101 or 102 for each side wall, with a rectangular casing or one of a greater number of sides. However, where a lesser number of full flaps are provided on each end then there are sides to the casing. I prefer that the narrow panels, such as 109 and 110, be provided on the blank; and that on those sides where the closure flap is omitted, the narrow panel be secured to the side panel in a suitable manner.

Where higher insulating value is required than is readily obtainable with a single insulating air space protecting any area of the container against transfer of heat to or from the container, I may provide additional heat insulating means between the inner and outer shell. In my patent application entitled Insulation sheets, Ser. No. 75,316 and filed April 20, 1936, I have shown a non-collapsible type of heat insulating filler; and in my application entitled Collapsible filler, Ser. No. 75,314 and also filed April 20, 1936, now matured into Patent, No. 2,231,982, I have shown a collapsible type of heat insulating filler. Either of these types of fillers are adapted to be inserted between the inner and outer shells of the casings which I have disclosed in the present application; and fillers of these types provide a plurality of air spaces in series to the passage of heat perpendicular to the wall of the container.

It will be understood that many changes may be made in my insulating casing, and that the particular modifications described are shown by way of illustration only, and are not intended to limit my invention within the meaning of the appended claim. Now having described my invention in a manner that it may be readily understood by one skilled in the art, I claim:

A collapsible insulating casing comprising an inner and an outer shell and dish-shaped closure members; said outer shell comprising a collapsible tube forming the outer side walls; said inner shell comprising side walls, end walls, flanges lengthwise of said side walls at the juncture of each to adjacent side walls; flaps for bottom and top walls, peripheral flange members of said inner shell along the top and bottom of said shell; said lengthwise flanges on said inner shell cooperating with said outer shell at its corners to secure the side walls of said inner and outer shells in predetermined spaced relationship with each other, thereby forming "dead" air insulating spacing covering the side walls of said casing; a member formed of sheet material enclosing the lower end of said casing to form a "dead" air insulating space covering the bottom end of said casing, and a similar member formed of sheet material enclosing the upper open end of said casing, and thereby forming a "dead" air insulating space covering the top end of said casing.

PHILIP ZALKIND.
